(57) **CLAIM**

We claim the ornamental design for a surge protector, as shown and described.

DESCRIPTION

FIG. 1 is an isometric top view of a surge protector; FIG. 2 is a top view of the surge protector of FIG. 1; FIG. 3 is a bottom view of the surge protector of FIG. 1; FIG. 4 is a front view of the surge protector of FIG. 1, the back of the transient voltage suppressor being symmetrical to the front;

FIG. 5 is a view of the left side of the surge protector of FIG. 1; and,

FIG. 6 is a view of the right side of the surge protector of FIG. 1.

The broken lines are shown for illustrative purposes only and form no part of the claimed design.
